HEN'S NEST

Charles Delos Firster, Warren, Ohio

Application November 2, 1935, Serial No. 48,027

5 Claims. (Cl. 119—50)

This invention relates to hens' nests and particularly to those nests designed for the purpose of permitting the entrance of a hen to the nest and then closing the entrance opening after her and immediately opening the door of an exit opening, so that the hen, after having laid an egg, may pass into another yard from those hens who have not laid.

The general object of this invention is to provide a nest of this character with very simple and effective means for securing the opening and closing of the exit and outlet openings and which is provided with means whereby the closing and opening of the doors may be prevented whenever desired, so that the nest will act as an ordinary nest.

Another object is to provide means of this character having vertically sliding doors and a lever actuated by the weight of the hen on the nest which will cause the closing of one door and the opening of the other door.

Other objects will appear in the course of the following description.

My invention is illustrated in the accompanying drawing wherein:

Figure 1 is a vertical section of a nest constructed in accordance with my invention;

Figure 2 is a fragmentary elevation of a portion of one side frame of the nest, the corresponding lever, a counterbalancing spring, and the means for latching the lever against actuation;

Figure 3 is a fragmentary cross-sectional view through the nest showing the two levers and the connected parts.

Referring to the drawing, it will be seen that the frame of the nest is formed of vertical angle irons 10 connected by transverse angle irons 11 and 12, the angle iron 12 being disposed above the lower ends of the vertical irons 10, so as to provide legs resting upon the floor 13. The walls of the nest are preferably of sheet metal as is the roof. The nest has opposed openings 14 and 15, the opening 14 being considered in the description as the entrance opening and the opening 15 is considered as the exit opening. The opening 14 will open into one yard while the opening 15 will open into another yard or enclosure.

The nest 16 is connected by a rivet 17 or equivalent member to one arm 18 projecting from the lower end of a lever 19. There are two of these levers disposed one on each side of the nest, each of these levers being T-shaped at its lower end, as illustrated in Figure 2. The nest 16 is also attached at one side by means of the rivet 20

to a vertical guide rod 21 which extends downward through the horizontal flange of the angle iron 12 and is guided therein. Each lever 19 is pivoted by means of a bolt or rivet 22 to an angle iron 23 which extends from front to rear of the nest, there being two of these angle irons, one on each side, the horizontal flange of this angle iron 23 being cut away, however, adjacent the lever as shown in Figure 1, so as to permit the operation of the levers. With this construction, it will be seen that when the hen enters and sits upon the nest that the weight of the hen will cause the depression of the arm 18, and this will cause the oscillation of the levers 19 in a clockwise direction in Figure 1. The lower end of each lever 19 is also provided with an arm 24, as shown in Figure 2, which is opposed to the arm 18. The arm 24 of one lever, as illustrated in Figure 1, is connected to the piston 25 of a dashpot 26, which acts as a cushioning means, this piston being less in diameter than the interior of the dashpot so as to permit the passage of air around it but simply retarding the movement of the lever. The arm 24 of the other lever 19, however, as illustrated in Figures 2 and 3 is connected by a spring 27 to the corresponding angle iron 12, so that when the hen gets off the nest, the spring 27 will pull the lever 19 over to the position shown in Figure 1 opening the door at the entrance and closing the door at the exit.

As illustrated in Figure 1, the door at the exit is designated 28 and is composed of flexibly connected strips sliding in vertical guides on each side of the door opening. The exit door 29 is of the same character as the door 28. Disposed at the upper end of the nest housing are angle iron guides 30 which extend transversely across the nest, each of these guides at its opposite ends being downwardly curved, as at 31, so that the doors 28 and 29, as they are pulled upward, will ride over this downwardly curved portion 31 and then ride along the rails 30. The inner ends of the doors 28 and 29 are connected by chains or like elements 32 to the upper ends of the levers 19. Thus when the lever 19 is in the position shown in Fig. 1, the door 28 will be closed while the door 29 will be drawn upward. When, however, a hen enters and sits upon the nest 16, the weight of the hen will cause the levers 19 to move from left to right in Figure 1, opening the door 28 and closing the door 29 which controls the entrance opening. This movement of the levers from the position shown in Figure 1 to the other position is retarded by the dashpot 26 so as to prevent a too sudden movement of these

levers and a too sudden descent of the nest which might startle the hen.

In case it is desired to prevent the automatic actuation of the doors 28 and 29 by the hen on the nest, I provide set screws 33, as shown in Figure 3, and also in Figure 2, extending through the vertical flanges of the angle irons 12, which when turned inward, impinge against the guide rods 21 and lock these guide rods from actuation. Thus the operator may open either door and then lock the levers against further movement, and the nest may then be used as an ordinary nest, having merely one opening for entrance or exit. Of course, when the screws 33 are turned outward, the guide bars are left free to shift vertically and the nest then becomes automatic in its action as regards the doors. It will be noted that the guide bars also prevent any lateral swinging movement of the nest or any tipping of the nest.

20 A floor 34 is provided on a level with the lower ends of the entrance and exit openings, the nest being set in an opening in this floor, as shown clearly in Figure 1. The walls of the nest housing will be made of sheet metal riveted or spot-welded to the frame. The frame elements will be welded together.

What is claimed is:—

30 1. A hen's nest of the character described, including a housing, opposed walls of the housing having one an entrance opening and the other an exit opening, sliding doors for the entrance and exit openings, a vertically movable nest disposed within said housing and levers one on each side of the nest operatively pivoted to the housing, each of said levers having an angular arm pivotally connected to the nest of each of said levers at its upper end being operatively connected to the doors, and means normally urging the nest upward and the levers to a position 40 where one door is closed and the opposed door open.

45 2. A hen's nest of the character described, including a housing, opposed walls of the housing having one an entrance opening and the other an exit opening, sliding doors for the entrance and exit openings, a vertically movable nest disposed within said housing and levers one on each side of the nest operatively pivoted to the housing, each of said levers having an angular arm pivotally connected to the nest and each of said levers at its upper end being operatively connected to the doors, spring means normally urging the nest upward and the levers to a position 55 where one door is closed and the opposed door open, and manually adjustable means for holding said levers from actuation when desired.

60 3. A hen's nest of the character described, including a housing, opposed walls of the housing having one an entrance opening and the other an exit opening, sliding doors for the entrance and exit openings, a vertically movable nest disposed within the housing and levers one on each side of the nest operatively pivoted to the housing, each of said levers having an angular arm

pivotedly connecting to the nest, and having an opposed angularly extending arm, each of said levers at its upper end being operatively connected to the inner ends of the doors whereby to cause their simultaneous movement as the levers are oscillated, a spring connected to the last-named arm of one lever and causing its depression and the elevation of the nest, and a cushioning means connected to the last-named arm of the other lever and acting to retard the simultaneous movement of both levers in either direction.

4. A nest of the character described, including a housing having opposed side walls and front and rear walls, the front and rear walls having 15 openings, a floor extending across the housing, opposed angle irons attached to the side walls and supporting said floor, the floor having an opening, a hen's nest disposed in said opening, oppositely disposed levers adjacent the side 20 walls, angle irons supporting the floor and to which the lower ends of the levers are pivoted, each lever at its lower end having an angularly projecting arm pivoted to the nest and an opposed arm, a dashpot operatively connected to the last-named 25 arm of one lever, a contractile spring operatively connected to the last-named arm of the other lever and urging the levers to a predetermined position, vertical guide members pivoted to the opposed arms of said levers 30 and extending downward through apertures in the frame of the nest, opposed doors controlling said openings and formed of flexibly connected sections, the inner ends of said sections being operatively connected to the upper ends of said 35 levers and supporting guides each having downwardly curved portions adjacent the openings in the walls over which guides the flexible doors operate.

5. A nest of the character described, including 40 a housing having opposed side walls and front and rear walls, the front and rear walls having openings, a floor extending across the housing, opposed angle irons attached to the side walls and supporting said floor, the floor having an 45 opening, a hen's nest disposed in said opening, oppositely disposed levers adjacent the side walls, angle irons supporting the floor and to which the lower ends of the levers are pivoted, each lever at its lower end having an angularly projecting 50 arm pivoted to the nest and an opposed arm, a dashpot operatively connected to the last-named arm of one lever, a contractile spring operatively connected to the last-named arm of the other lever and urging the levers to a predetermined 55 position, vertical guide members pivoted to the opposed arms of said levers and extending downward, and means engageable with the guide members to lock them against vertical movement whereby to lock the levers against movement and thereby hold one of said doors in an open position and the other door in a closed position.

CHARLES DELOS FIRSTER.
